UNITED STATES PATENT OFFICE.

FRED HULL ABBOTT, OF CRYSTAL FALLS, MICHIGAN.

RECEPTACLE FOR POWDER.

No. 851,474.

Specification of Letters Patent.

Patented April 23, 1907.

Application filed February 10, 1906. Serial No. 300,459.

To all whom it may concern:

Be it known that I, FRED HULL ABBOTT, a citizen of the United States, and a resident of Crystal Falls, in the county of Iron and State of Michigan, have invented a new and Improved Receptacle for Powder and the Like, of which the following is a full, clear, and exact description.

This invention relates to receptacles or boxes for containing and measuring out powder or analogous material and is especially useful in connection with cans for tooth powder.

The object of this invention is to provide an efficient and inexpensive device which will securely retain the powder or like substance when not in use, and at the same time permit the contents to be readily dispensed therefrom in small quantities.

The invention consists in the construction and combination of parts, which will be set forth hereinafter and particularly pointed out in the claims.

Reference is to be had to the accompanying drawings which illustrate as an example the preferred embodiment of my invention, in which drawings similar characters of reference indicate like parts in the several views, and in which

Figure 1 is a perspective view of the invention with the receptacle partially broken away to show the construction more clearly, and illustrating the device in a normal position; Fig. 2 is a similar view showing a part of the apparatus in a different position; and Fig. 3 is a partial vertical cross section.

Referring more particularly to the parts, the receptacle or box 1 may be of the usual or any desired type for containing tooth powder or analogous material. On the inner side of a wall of this receptacle I provide a sleeve 2 in which a rod or plunger 3 is movably mounted, the upper portion of this plunger passing through and fitting closely in an opening in the top 4 of the receptacle. The plunger is provided with a shoulder 5 to prevent its passing more than a certain distance through the opening in the top of the receptacle and to completely close the opening, thereby preventing the escape of the powder when the receptacle is not in use. The upper part of

the plunger is provided with a depression or a perforation 6 to contain a certain quantity of the powder. The plunger is normally held in position with the shoulder or stop 5 against the receptacle top 4, by means of a coiled or helical spring 7, one end of which is looped through an opening 8 in the sleeve 2, while the other extremity is suitably fastened to a pin 9 in the lower end of the plunger 3. This pin 9 may also serve as a stop, against the edge of the sleeve, to limit the motion of the plunger.

This device may be conveniently operated with one hand. The receptacle is held in the hand and the plunger pressed down with the forefinger. A portion of the contents is allowed to enter the opening in the plunger, if necessary by inverting the receptacle. When the plunger is released through the removal of the finger, it is returned to its normal position by the spring, and carries with it in the opening at its upper extremity the powder which may then be dropped, for example, upon a tooth brush.

Having thus described the preferred form of my invention, what I claim as new and desire to secure by Letters Patent is:

1. A receptacle having an opening, a bar constituting a plunger, within said receptacle, and having a constricted end forming a shoulder adapted to limit the projection of said plunger through said opening, means within said receptacle for guiding said plunger, and a spring adapted normally to project said plunger through said opening, said plunger having a recess at said constricted end for carrying a quantity of powder or the like.

2. A receptacle having a sleeve on an inner wall thereof, a bar constituting a plunger slidably mounted in said sleeve and having a constricted end forming a shoulder adapted to limit the projection of said plunger from the receptacle, said end having a recess for carrying a quantity of powder or the like, and a spring secured to said plunger and to said sleeve whereby said plunger is projected from said receptacle.

3. A receptacle having a sleeve on an inner wall thereof, a plunger slidably mounted in said sleeve and adapted to project from said receptacle, said plunger having a recess for

carrying a quantity of powder or the like and a pin adapted to engage an edge of said sleeve to constitute a stop limiting the projection of said plunger from said receptacle, and a spring secured to said pin and to said sleeve adapted normally to project said plunger from said receptacle.

In testimony whereof I have signed my name to this specification in the presence of two subscribing witnesses.

FRED HULL ABBOTT.
